Fig. 1

A technical drawing of a curved metal strip. The strip is labeled with the number '1' at its left end. Along its length, there are several features labeled with numbers: '28' at the top left, '25' at the bottom center, and '26' at the top right. The strip is shown in perspective, with its ends curving upwards and outwards.

PACKAGE FOR CARBON PAPER

Edward W. Curtis, Jr., Langhorne, Pa., assignor
to Underwood Elliott Fisher Company, New
York, N. Y., a corporation of Delaware

Application December 31, 1941, Serial No. 425,149

2 Claims. (Cl. 206—63)

This invention relates to packages for sheets of carbon paper.

The invention relates particularly to packages for sheets of carbon paper of odd sizes although certain features of the invention may be embodied in constructions in which may be packed carbon sheets of standard size as well as odd sized sheets.

A large proportion of the carbon sheets sold by manufacturers of carbon paper often consists of odd sized sheets. It has been a difficult problem, in plants in which carbon paper is manufactured, to pack odd sizes of such paper for shipment economically. On account of the number of sizes of the carbon sheets, when they are packed in boxes, it is necessary to maintain a large number of sizes of boxes in stock, and even then orders will often be received for a size for which there are no boxes. The paper then either is packed in non-fitting boxes or the shipment is held until boxes are secured to fit the same. The maintaining of a large number of boxes of different sizes in stock involves considerable expense.

One object of the present invention is to improve the construction of packages for sheets of carbon paper and to provide a novel package in which may be packed alternatively a plurality of different sizes of sheets.

Another object of the invention is to produce a package for carbon paper in which a relatively large number of different sizes of sheets may be efficiently packed in stacked arrangement.

Another object of the invention is to produce a package for sheets of carbon paper of odd sizes in which the packages are of standard size so that they may be packed in standard size wooden boxes or other containers employed for shipping wholesale quantities of standard size sheets.

With the above and other objects in view, the invention consists in a package involving the novel and improved features hereinafter described and particularly pointed out in the claims, the advantages of which will be readily understood and appreciated by those skilled in the art.

The invention will be clearly understood from the accompanying drawings illustrating the invention in its preferred form and the following detailed description of the construction therein shown.

In the drawings:

Fig. 1 is a plan view of a container for carbon paper embodying the invention, illustrating the parts of the container in open condition to receive the carbon sheets,

Fig. 2 is a sectional view of the container taken substantially on the line 2—2 of Fig. 1,

Fig. 3 is a plan view of the container illustrating a sheaf or pack of carbon sheets in position in the inner folder with the flaps of said folder folded over upon said sheets,

Fig. 4 is a sectional view taken substantially on the line 4—4 of Fig. 3,

Fig. 5 is a plan view illustrating the flaps of both the inner and outer folders folded over upon the sheaf of carbon sheets,

Fig. 6 is a plan view similar to Fig. 3 except that a sheaf of carbon paper of a different size is enclosed in the inner folder,

Fig. 7 is a plan view illustrating the container with the sheaf of carbon paper shown in Fig. 6 placed therein and with the flaps of both the inner folder and those of the outer folder folded over upon the sheaf,

Fig. 8 is a sectional view, to some degree diagrammatic, taken substantially on the line 8—8 of Fig. 7,

Fig. 9 is a view similar to Figs. 3 and 6 except that a sheaf of carbon paper of a still different size is inserted in the container,

Fig. 10 is a sectional view taken substantially on the line 10—10 of Fig. 9, and

Fig. 11 is a plan view of the container with the sheaf of carbon paper shown in Fig. 9 inserted therein and with the flaps of the inner and outer folders folded over upon said sheaf.

In the form of the invention illustrated in the drawings, the package or container comprises an outer folder indicated at 2 preferably made of relatively heavy paper or relatively thin, light, flexible cardboard, which will be referred to hereinafter, generally, as paper board, and an inner folder indicated at 24 made of similar material. The folder 2 comprises a central panel indicated at 6, of rectangular outline, from which extend two lateral flaps indicated at 8 and two end flaps indicated at 10. To enable the flaps readily to be folded over into positions opposite the central panel, the folder is provided with two sets of weakened lines indicated respectively at 12, 12a and 14, 14a, one set between the body of each of the flaps 8 and the central panel 6, and with two sets of weakened lines 16, 16a and 18, 18a, one set between the body of each of the flaps 10 and

50 said panel. The lines of each of these pairs are spaced preferably by a distance somewhat greater than that of the thickness of the sheaf of carbon sheets containing the maximum number of sheets which will be shipped in the package. One of the flaps 8 is provided with a tongue 20 arranged to

55

be inserted in a slit 22 in the opposite flap when these flaps are folded over into closed position to lock the same together.

The folder 24 is provided with a central panel indicated at 25 which may be centrally located with relation to the panel 6 as shown in the drawings, and is secured to the latter panel in any suitable or convenient manner. This folder is provided with two lateral flaps 26 and 28 extending outwardly from the central panel and with end flaps 30 and 32.

The flap 30 of the folder 24 is provided with pairs of weakened lines 34 and 34a, 36 and 36a and 38 and 38a to enable this flap to be readily folded inwardly along these lines. The lines 34 and 34a respectively, are located slightly inside the lines 16 and 16a of the corresponding flap 10 of the folder 2. The flap 32 of the folder 24 is formed with pairs of weakened lines 40 and 40a, 42 and 42a and 44 and 44a to enable this flap readily to be folded inwardly along these lines. The lines 40 and 40a are located respectively slightly inside the lines 18 and 18a of the adjacent flap 10 of the folder 2. The flap 26 is provided with pairs of weakened lines 46 and 46a, 48 and 48a, and 50 and 50a to enable this flap readily to be folded inwardly along these lines. The lines 46 and 46a respectively, are located slightly inside the corresponding lines 12 and 12a of the corresponding flap 8 of the folder 2. The flap 28 of the folder 24 is formed with pairs of weakened lines 52 and 52a, and 54 and 54a to enable this flap readily to be folded inwardly along these lines. The lines 52 and 52a respectively, are located slightly inside the respective lines 14 and 14a of the corresponding flap 28 of the folder 2.

The weakened lines of the two folders are formed by scoring or perforating the material of the folders or in any other convenient manner. With the above construction a large number of sizes of carbon sheets may be readily packed for shipment. Figs. 3, 4 and 5 show a sheaf or pack 56 of carbon sheets placed in the package. This sheaf contains sheets of the largest size which the package is arranged to accommodate. These sheets may be of a standard size. These sheets are of a size slightly less than that of the central panel 6 of the folder 2. In packing such a sheaf, with the flaps all unfolded as shown in Fig. 1, the sheaf is placed upon the inside folder 24 with the edges of the sheaf just inside the outer lines of the panel 6 of the outer folder 2 and the flaps 30, 32, 26 and 28 of the inner folder are folded over inwardly on the pack along the lines 34, 34a, 40, 40a, 46, 46a, and 52, 52a as shown in Figs. 3 and 4. The flaps 8 and 10 are then folded over inwardly on the pack along the lines 16, 16a, 18, 18a, 12, 12a and 14, 14a as shown in Fig. 5, with the flaps 10 on the inside and the tongue 20 is inserted in the slit 22 to lock the flaps of the outer envelope in place.

Figs. 6, 7 and 8 show the manner in which a sheaf 58 of sheets of carbon of another size is packed in the package. The sheets of this pack are of substantially a length to fit between the lines 36a, 42a and of a width to fit between the lines 48a and 54a of the inner envelope. In packing this sheaf, the sheaf is placed upon the inner folder just inside the lines 36a, 42a, 48a and 54a and the flaps 30, 32, 26 and 28 are folded over inwardly upon the same along the lines 36, 36a, 42, 42a, 48, 48a and 54, 54a into substantially the positions shown in Fig. 6. The flaps 10 and 8 of the outer folder are then folded over inwardly along the lines 16, 16a, 18, 18a, 12, 12a and 14,

14a upon the inner folder with the flaps 10 on the inside as shown in Fig. 7, and the tongue 20 is inserted in the slit 22 to lock the flaps of the outer folder in position.

5 Figs. 9, 10 and 11 show the manner in which a sheaf 60 of sheets of carbon paper of still another size is packed in the package. The sheets of this sheaf are of substantially a length to fit between the lines 38a and 42a of the inner folder and of a width to fit between the lines 46a and 54a of said folder. In packing the sheaf 60, said sheaf is placed on the inner folder 24 with its edges just inside the lines 38a, 42a, 46a and 54a of said folder and the flaps 30, 26, 32 and 28 are folded over inwardly upon the sheaf along the lines 38, 38a, 42, 42a, 46, 46a and 54, 54a respectively, into the positions shown in Figs. 9 and 10. The flaps 10 and 8 of the outer folder are then folded over inwardly upon the inner folder and the sheaf 20 contained therein along the lines 16, 16a, 18, 18a, 12, 12a and 14, 14a into the position shown in Fig. 11 with the flaps 10 on the inside and the tongue 20 is inserted in the slot 22 to lock the flaps in position.

25 The spacing between the weakened lines of each pair of the inner folder is for the purpose of accommodating the thickness of the sheaf of sheets packed in the same. The portion of each flap between said lines fits along the edges of the 30 sheets of a sheaf in the manner shown clearly in Figs. 4, 8 and 10.

The flaps of the inner folder 24 may be folded along different combinations of the weakened lines to accommodate packs of sheaves of sheets 35 having a number of different lengths and a number of different widths. The construction shown is designed for the packing of sheaves of forty two different sizes. The weakened lines on the 40 folders may, of course, be varied in positions as found desirable for the packing of sheaves of any sizes and there may be as many of these weakened lines as desired.

With the above construction, not only may a 45 pack of sheets of the largest size which the outer folder 2 is constructed to accommodate be packed but the smaller sizes also may be quickly and easily packed in the package and are snugly held therein without the use of additional packing 50 material. Thus in the cases shown, the sheaves 58 and 60 of carbon sheets are firmly and securely held in the package from movement therein, when the package is closed.

The outer folder may be of a standard size and 55 the packages may be packed in standard size boxes or other containers for shipment in wholesale lots.

It is to be understood that, except as defined in the claims, the invention is not limited to the 60 particular construction and arrangement of parts of the illustrated embodiment of the invention but that the invention may be embodied in other forms within the scope of the claims.

Having explained the nature and object of the 65 invention and having illustrated and described a construction embodying the invention in its preferred form, what is claimed is:

1. A package for sheets of carbon paper comprising an outside folder of relatively thin, flexible paper board having a substantially rectangular central panel, a plurality of flaps extending from said panel, each having weakened transverse substantially parallel fold lines and arranged to be folded inwardly along said lines toward said panel to form side walls of an outer

casing and an enclosing cover opposite the panel, an inside folder of similar material having a substantially rectangular central panel of less length and width than the first panel attached directly to the central panel of the outside folder and a plurality of flaps extending from said central panel and respectively having substantially the same width throughout as the corresponding dimensions of the latter panel, said flaps extending outwardly different distances from the latter panel and having transverse fold lines along which the flaps are arranged to be folded inwardly toward said panel, said flaps being of sufficient length to extend beyond the margins of said panel of the outside folder and one or more of said flaps of the inside folder having weakened fold lines located at different distances from the corresponding center line of the folder to enable the flaps to be folded at different points for different sizes of carbon sheets placed therein.

2. A package for sheets of carbon paper comprising an outside folder of relatively thin, flexible paper board having a substantially rectangular central panel, a plurality of flaps extend-

ing from said panel, each having weakened transverse substantially parallel fold lines and arranged to be folded inwardly along said lines toward said panel to form side walls of an outer casing and

5 an enclosing cover opposite said panel, an inside folder of similar material having a central panel of less length and width than the first panel attached directly to the central panel of the outside folder and a plurality of flaps extending from said central panel and respectively having substantially the same width throughout as the corresponding dimensions of the latter panel, said flaps extending outwardly different distances from the latter panel and having trans-

10 verse fold lines located respectively adjacent said fold lines on the flaps of the outer panel along which the flaps on the inside folder are arranged to be folded inwardly toward the central panel of said folder, one or more of said flaps of the inside folder having weakened fold lines located at

15 different distances from the corresponding center lines of the folder to accommodate different sizes of carbon sheets placed therein.

EDWARD W. CURTIS, JR.
